US0D1027035S

(12) **United States Design Patent** (10) **Patent No.:** **US D1,027,035 S**
(45) **Date of Patent:** **** May 14, 2024**

(54) **ELECTRONIC SHELF LABEL**

(71) Applicant: **SES-imagotag GmbH**, Fernitz-Mellach (AT)

(72) Inventor: **Peter Groiss**, Laakirchen (AT)

(73) Assignee: **SES-IMAGOTAG GmbH**, Fernitz-Mellach (AT)

(**) Term: **15 Years**

(21) Appl. No.: **29/796,059**

(22) Filed: **Jun. 22, 2021**

(30) **Foreign Application Priority Data**

Dec. 23, 2020 (DE) 402020101254.8

(51) **LOC (14) Cl.** **20-03**

(57) **CLAIM**

The ornamental design for an electronic shelf label, as shown and described.

DESCRIPTION

FIG. 1 is a rear perspective view of the electronic shelf label;

FIG. 2 is a front perspective view thereof;

FIG. 3 is a rear side elevational view thereof;

FIG. 4 is a front side elevational view thereof;

FIG. 5 is a right side elevational view thereof;

FIG. 6 is a left side elevational view thereof;

FIG. 7 is a bottom plan view thereof; and,

FIG. 8 is a top plan view thereof.

The broken line portion of the figure drawings is included to show portion of the article that form no part of the claimed design.

1 Claim, 6 Drawing Sheets
